ARMORED RAIL BOND

Harold H. Febrey, Cleveland, Ohio, assignor to
The American Steel and Wire Company of New
Jersey, a corporation of New Jersey

Application March 26, 1948, Serial No. 17,312

2 Claims. (Cl. 238—14.7)

1

This invention relates to rail bonds, and more especially to the association of helically-preformed armor rod reinforcements with rail bonds and their disposition between the rail and the splice bar at the joint of application.

Rail bonds should afford:

- (1) Low resistance
- (2) Long fatigue life
- (3) Accommodation of normal rail movements
- (4) Certainty to fail in abnormal rail movements
- (5) Facility of installation
- (6) Facility of inspection and maintenance.

One of the bonds finding popular acceptance as having these requisites is the rail head bond, which is small, massive, easily installed, and readily accessible for inspection and repair. The rail-head type of bond, however, being exposed, is vulnerable to damage from railroad rolling stock and from heating which occurs when the rail ends are built up by welding or are being heat-treated. Long sections of track have been stripped of such bonds by hanging rigging or broken undergear projecting from beneath passing trains which shears off the bonds and disrupts the signal current in a manner similar to a rail break or track failure.

It has been proposed to dispose rail bonds below the head of the rail at the rail web or at the base, and, in order to obtain maximum protection, to install such bonds behind the splice bars. In the case of outside bonds, since such bonds are of necessity of considerable length in order to span the splice bar, they admit of abnormal rail movements even to complete track failure at the joint without themselves failing to give warning of the existing danger by impairment of the signal current. In the case of inside bonds, the conductor was delimited in size by the size of terminal which could be threaded between the splice bar and rail, and this resulted in an increased length to diameter ratio which rendered the bond overly flexible and incapable of sustaining its own weight over the span of the joint. Not only did such a bond present difficulties of installation, as is evident in trying to push any long, limp body through a confined space, but, once in place, the bond became subject to dropping into the crevice formed by the base of the splice bar and the rail web adjacent the base of the rail, where it was pinched and chafed and quickly destroyed by the great forces of motion attendant upon the passage of trains. The only alternative was to predispose the bonds before the splice bars were bolted on during the track laying operation, but

2

this interfered with the laying of track and is held in disfavor by the track gangs.

It is the main object of this invention to provide an inside bond which will have the requisites of the rail head bond without the disadvantages usually associated with such bonds, as discussed above. Other objects and advantages herein-after to appear will be better understood by reference to the accompanying specification considered in conjunction with the accompanying drawings, in which:

Fig. 1 is a plan view of a rail bond adaptable to the invention.

Figs. 2 and 4, and 3 and 5, are side and end views, respectively, of helically-preformed armor rods for association with rail bonds similar to Fig. 1.

Figs. 6, 9, 10, and 11, are side views and sectional view of the rail bond-armor rod combinations according to this invention, Fig. 10 being regarded as a section along line 10—10; Fig. 9.

Fig. 7 is a fragmentary side elevational view of a conventional rail joint construction showing a bond after the present invention installed behind the splice bar.

Fig. 8 is an enlarged sectional view taken at 8—8, Fig. 7; while

Figs. 12 to 15, inclusive, show modifications and certain details of the invention.

In the drawings, in which correspondence between the reference characters and identified parts obtains throughout, rail bonds 10, comprised of a conductor 11 and terminals 12 are constructed to a size readily to be inserted between a splice bar 13, a railway rail 14, and associated track bolts 15, and of a length sufficient to project beyond the ends of the splice bar to points of attachment to the rail webs, as shown in Fig. 7. This attachment may be effected by an expanding pin 12a for the type shown in Fig. 6, or may be accomplished by welding or any other suitable method.

In order to augment the effective diameter of the rail bond, and to make it stiff and capable of sustaining its own weight for the length involved (usually a minimum of three feet is required for this type of installation), a helically-preformed armoring of hard-drawn wires 16 having an internal helical diameter substantially equal to the external diameter of the conductor 11 is disposed along its length for a distance equal to or greater than the length of the splice bar 13. As appears in Fig. 8, the armor rod 16 prevents the conductor from being pinched between the splice bar and rail and provides a wear-resistant cover for the

conductor which absorbs the wear and abrasion normally to befall the latter.

The armoring may comprise one or more of the armor rods 16, either of the conventional type of constant pitch length, as represented in Figs. 2 and 6, or of the type having a diminishing pitch length 17 adjacent its ends, as shown in Figs. 4, 9, and some of the other figures. Since the conductor 11 is flexible, it is desirable to have the diminishing pitch length 17 on the helix more completely to encircle the conductor at the points where it is led to the terminal fastenings on the rail web, thus to preclude its accidental disengagement from the terminal wraps of the armor rod.

Fig. 11 illustrates the application of a plurality of armor rods in overlapping relation. These may be identically formed and coextensively disposed about the conductor, or they may be formed so that only the opposite outer ends of each rod have the diminished pitch length 17, to be applied to the conductor whereby only the regular helical portions overlap and leave the portions 17 projecting beyond the ends of the overlapping portion.

In Figs. 12 and 13, the conductor 11 is completely enclosed by a tubing of armor rods 16, which may also include the diminished pitch length portions 17, but which by virtue of the complete encirclement and mutual sustentation of the rods, renders this construction unnecessary.

Since the armor rods 16 are helical, they have the capabilities of being bent or looped with great flexibility without axial displacement relative to the conductor, and this notwithstanding their essential stiffness and rigidity. Hence, an expansion loop 18, as shown in Fig. 15, and as is indicated by broken lines in Fig. 7, may be provided by crimping the conductor after the armoring is in place upon it, or by preforming armor rods in this manner. Similarly, as shown in Fig. 14, the armoring may be curved axially adjacent its ends fairly to lead the conductor and its terminal portion to its place of attachment to the rail.

Although it has not been specifically illustrated, it will be understood that the armored bond of the present invention may be disposed on top of the track bolts 15, as shown at 19 in dotted lines, Fig. 8, as well as beneath them as otherwise indicated in this figure.

I claim:

1. In combination, a railroad rail and splice bar assembly comprising a rail joint, a rail bond

comprising a flexible cable element longer than the splice bar extending between the latter and the rail and projecting beyond the ends of the splice bar with terminal portions attached to the rail, and a helically-preformed armor rod having a pitch length several times greater than the diameter of said cable element encircling the latter at least around its portions enclosed between the splice bar and the rail, said helically-preformed armor rod having a preformed helix of gradually diminishing pitch length adjacent to the terminal portions of said cable to confine and hold the latter.

2. In combination, a railroad rail and splice bar assembly comprising a rail joint, a rail bond 15 comprising a flexible cable element longer than the splice bar extending between the latter and the rail ends and projecting beyond the ends of the splice bar with terminal portions attached to the rails, a helically preformed armor rod 20 encircling said cable element, said armor rod being of a size and strength snugly to encompass said cable element and to stiffen and support the same so that they may be pushed between the rail and splice bar from one end, said armor 25 rod being of open pitch to permit installation upon said cable element without necessitating deformation exceeding its elastic limit while being sufficiently confining to support said cable element so that its longitudinal axis is essentially coincident with the helical axis of the armor rod throughout their coextensive portions, said portions being of an overall diameter sufficiently great to protect the cable element against 30 pinching between the several parts of said joint.

HAROLD H. FEBREY.
